PLAY DRESS OR THE LIKE

James Brooks, Chicago, Ill.

Application August 19, 1948, Serial No. 148,189

Term of patent 3½ years

(Cl. D3—25)

To all whom it may concern:

Be it known that I, James Brooks, a citizen of the United States of America, residing at Chicago, in the county of Cook, and State of Illinois, have invented a new, original, and ornamental Design for a Play Dress or the like, of which the following is a specification, reference being had to the accompanying drawing, forming part thereof.

Fig. 1 is a front elevational view of a play dress or the like showing my new design.

Fig. 2 is a rear view.

Fig. 3 is a side view of Fig. 1.

I claim:

The ornamental design for a play dress or the like, as shown.

JAMES BROOKS.
